UNITED STATES PATENT OFFICE

HORACE H. RAYMOND, OF BERLIN, CONNECTICUT, ASSIGNOR TO THE STANLEY WORKS,
OF NEW BRITAIN, CONNECTICUT, A CORPORATION OF CONNECTICUT

DESIGN FOR A CABINET CATCH

Application filed March 1, 1929. Serial No. 30,268. Term of patent 14 years.

To all whom it may concern:

Be it known that I, HORACE H. RAYMOND, a citizen of the United States, and a resident of Berlin, in the county of Hartford, State of Connecticut, have invented a new, original, and ornamental Design for a Cabinet Catch, of which the following is a specification, reference being had to the accompanying drawing, forming part hereof.

In the accompanying drawing, Figure 1 is a front elevational view of a cabinet catch showing my new design, and

Fig. 2 is a side view thereof.

I claim:

The ornamental design for a cabinet catch, as shown.

HORACE H. RAYMOND.
